(57) **CLAIM**

The ornamental design for an eye glass frame, as shown and described.

DESCRIPTION

FIG. 1 is a front side view of the eye glass frame;
FIG. 2 is a side view of the eye glass frame of FIG. 1, the
opposite side view being a mirror image;
FIG. 3 is a top side view of the eye glass frame of FIG. 1;
FIG. 4 is a perspective view of the eye glass frame of FIG. 1;
and,
FIG. 5 is a bottom perspective view of the eye glass frame of
FIG. 1.
The broken lines showing the lens are for illustrative purposes
only and form no part of the claimed design.
